MARTIN L. UNGRICH, OF BROOKLYN, NEW YORK

TONE-AMPLIFYING DEVICE FOR STRINGED MUSICAL INSTRUMENTS

Application filed April 3, 1928. Serial No. 267,010.

This invention relates to sound amplifiers, and has particular reference to an improved means for effecting the tone amplification of violins, cellos, violas or similar stringed instruments.

One of the outstanding objects of the present invention is to provide an accessory for violins or other stringed instruments of this nature which functions to amplify the tones while obtaining a fuller, richer and mellower quality.

More specifically, the invention comprehends, particularly in connection with violins, cellos or similar stringed instruments, the employment of one or more amplifying elements disposed within the body and supported from the tail block to augment the tone values produced by the instrument.

Other objects reside in the provision of an improved tone amplifying means for stringed instruments of the character set forth, which means is simple in construction, inexpensive to produce and highly efficient in its purpose.

With the above recited and other objects in view, reference is had to the following description and accompanying drawings, in which there is exhibited one example or embodiment of the invention, while the claims define the actual scope of the same.

In the drawings:

Figure 1 is a horizontal sectional plan view through the instrument body with the amplifying means arranged therein.

Figure 2 is a transverse sectional view therethrough taken approximately on the line 2—2 of Figure 1.

Referring to the drawings by characters of reference, 10 designates generally the instrument body which includes the marginal wall 11 and the top and bottom walls 12 and 13.

The amplifying means includes one or more bowl shaped elements 14 which are preferably in the nature of a segment of a hollow sphere having the concave face 15 disposed

upwardly. The elements are of gradually decreasing thickness from the central portion 16 to the outer edge 17 which is thin and sharp as illustrated, the cross sectional configuration of the elements being approximately of crescent shape. In practice, where a plurality of the elements are used they are of relatively different vibratile frequencies with the resonant element of lowest frequency disposed at a point adjacent the bass side of the instrument and gradually increasing in the frequency of vibration to which they will respond toward the opposite side of the instrument. That is, the resonant element which would respond principally to the vibration of the bass string of the instrument would be disposed within the instrument body adjacent the side with which the bass string is associated; the resonant element which would mainly respond to the vibrations of the highest pitched string would be disposed within the instrument body adjacent the side with which the highest pitched string is associated; and between these extremes would be positioned one or more resonant elements which would respond principally to the vibrations of the intermediate-tone-giving strings. Thus it will be seen that any number of variously resonant elements may be used to respond to the tones of the strings or by combinations of adjoining variously resonant elements produce half-tone effects. In practice, each bowl element is provided with a shank 18 which extends radially therefrom and which is anchored in the tail block 19 which is usually provided within the rear of the body portion of the instrument. In use, the elements function to amplify the tones which are produced by the instrument and serve to produce a fuller, richer and mellower tone quality.

What is claimed is:

1. The combination with a stringed instrument of a tone amplifying means including a plurality of bowl shaped elements of rela-

tively different sizes supported within the confines of the instrument body.

2. The combination with a stringed instrument of a tone amplifying means including a plurality of bowl shaped elements of relatively different sizes supported within the confines of the instrument body, each of said elements having a shank for connecting the same to the instrument.
- 10 3. The combination with a stringed instrument of a tone amplifying means including a bowl shaped element supported within the confines of the instrument body, said element being of cross sectional crescent shape.
- 15 4. A tone amplifying means for violins and other similar stringed musical instruments including a bowl shaped element of gradually decreasing thickness from the central portion to the marginal edge.
- 20 5. A tone amplifier for stringed musical instruments, including a plurality of variously-resonant elements, said elements being bowl shaped.
- 25 6. A tone amplifier for stringed musical instruments, including a plurality of variously-resonant elements, said elements being bowl shaped, their thickness diminishing from center to marginal edge.
- 30 7. The combination with a stringed musical instrument of a tone amplifier, including a plurality of variously-resonant elements, said elements being bowl shaped, their thickness diminishing from center to peripheral edge, said elements being positioned adjacent
- 35 the tail of the instrument.
8. The combination with a stringed musical instrument of a tone amplifier, including a plurality of variously-resonant elements, said elements being bowl shaped, their thickness diminishing from center to peripheral edge, said elements being positioned adjacent the lower end of the instrument and within the same, said elements being spaced apart each element being equidistant from
- 40 the center of the instrument end.
9. The combination of a stringed musical instrument and tone amplifying means therefor, said means including a plurality of resonant bowl-shaped elements and a plurality of shanks therefor, extending radially from the tail block of the instrument for supporting said resonant elements, each of said elements being adapted for sympathetic vibration with certain of the strings of the instrument.
- 45 10. The combination of a stringed musical instrument and tone amplifying means therefor, said means including a plurality of resonant bowl-shaped elements and a plurality of shanks therefor, extending radially from the tail block of the instrument for supporting said resonant elements, each of said resonant elements differing from the others in the vibratile frequencies to which it will respond.
- 50 11. The combination of a stringed musical

instrument and tone amplifying means therefor, said means including a plurality of resonant bowl-shaped elements and a plurality of shanks therefor, extending radially from the tail block of the instrument for supporting said resonant elements, each of said resonant elements differing from the others in the vibratile frequencies to which it will respond, each of said resonant elements being arranged adjacent the string with which it is in sympathy.

Signed at New York, in the county of New York and State of New York, this 2nd day of April, A. D. 1928.

MARTIN L. UNGRICH.
